CLAIM

The ornamental design for a footwear care machine as shown and described.

DESCRIPTION

FIG. 1 is a front perspective view of a footwear care machine showing a new design;

FIG. 2 is a bottom perspective view thereof;

FIG. 3 is a front view thereof;

FIG. 4 is a rear view thereof;

FIG. 5 is a left-side elevation view thereof;

FIG. 6 is a right-side elevation view thereof;

FIG. 7 is a top plan view thereof;

FIG. 8 is a bottom plan view thereof;

FIG. 9 is an enlarged detail view taken from portion 9 in FIG. 2 showing the sterilizing dryer;

FIG. 10 is an enlarged detail view taken from portion 10 in FIG. 2 showing the sterilizing dryer in an alternate configuration thereof;

FIG. 11 is an enlarged detail view taken from portion 11 in FIG. 2 showing the sterilizing drying in an environment of use;

FIG. 12 is an enlarged detail view taken from portion 12 in FIG. 2 showing the sterilizing dryer in an alternate configuration, in an environment of use thereof; and,

FIG. 13 is a perspective view showing the sterilizing dryer in an alternate configuration.

The dot-dash lines in FIGS. 9 and 10 and the dot-dot-dash lines in FIGS. 11 and 12 annotate the enlarged views and form no part of the claimed design. The even-dash broken lines of the footwear in FIGS. 11 and 12 are for environment purpose only and form no part of the claimed design. The even-dash broken lines represent portions of the footwear care machine that form no part of the claimed design.
